(57) **CLAIM**

The ornamental design for a frame for a table top, as shown and described.

DESCRIPTION

FIG. 1 is an upper perspective view of an exemplary frame for a table top;

FIG. 2 is an upper perspective view of the frame shown in FIG. 1;

FIG. 3 is a top view of the frame shown in FIG. 1;

FIG. 4 is a front view of the frame shown in FIG. 1;

FIG. 5 is a bottom view of the frame shown in FIG. 1;

FIG. 6 is a rear view of the frame shown in FIG. 1;

FIG. 7 is a left side view of the frame shown in FIG. 1; and,

FIG. 8 is a right side view of the frame shown in FIG. 1.

The broken lines shown in the figures are for illustrative purposes only and form no part of the claimed design.

1 Claim, 3 Drawing Sheets
